(57) **CLAIM**

The ornamental design for a cross bolt for firearm, as shown and described.

DESCRIPTION

FIG. 1 is an isometric view of a first embodiment of a cross bolt for firearm in accordance with the present disclosure; FIG. 2 is a left side elevation view of the cross bolt for firearm of FIG. 1;

FIG. 3 is a right side elevation view of the cross bolt for firearm of FIG. 1;

FIG. 4 is a front elevation view of the cross bolt for firearm of FIG. 1;

FIG. 5 is a rear elevation view of the cross bolt for firearm of FIG. 1;

FIG. 6 is a top view of the cross bolt for firearm of FIG. 1;

FIG. 7 is a bottom view of the cross bolt for firearm of FIG. 1;

FIG. 8 is an isometric view of a second embodiment of a cross bolt for firearm in accordance with the present disclosure;

FIG. 9 is another isometric view of the cross bolt for firearm of FIG. 8;

FIG. 10 is another isometric view of the cross bolt for firearm of FIG. 8;

FIG. 11 is another isometric view of the cross bolt for firearm of FIG. 8;

FIG. 12 is a left side elevation view of the cross bolt for firearm of FIG. 8;

FIG. 13 is a right side elevation view of the cross bolt for firearm of FIG. 8;

FIG. 14 is a front elevation view of the cross bolt for firearm of FIG. 8;

FIG. 15 is a rear elevation view of the cross bolt for firearm of FIG. 8;

FIG. 16 is a top view of the cross bolt for firearm of FIG. 8;

FIG. 17 is a bottom view of the cross bolt for firearm of FIG. 8;

FIG. 18 is an isometric view of a third embodiment of a cross bolt for firearm in accordance with the present disclosure;

FIG. 19 is another isometric view of the cross bolt for firearm of FIG. 18;

FIG. 20 is another isometric view of the cross bolt for firearm of FIG. 18;

FIG. 21 is another isometric view of the cross bolt for firearm of FIG. 18;

(Continued)

FIG. 22 is a left side elevation view of the cross bolt for firearm of FIG. 18;
 FIG. 23 is a right side elevation view of the cross bolt for firearm of FIG. 18;
 FIG. 24 is a front elevation view of the cross bolt for firearm of FIG. 18;
 FIG. 25 is a rear elevation view of the cross bolt for firearm of FIG. 18;
 FIG. 26 is a top view of the cross bolt for firearm of FIG. 18;
 FIG. 27 is a bottom view of the cross bolt for firearm of FIG. 18; and,
 FIG. 28 is an isometric view of a cross bolt for firearm in accordance with the present disclosure.
 The broken lines showing portions of the cross bolt for firearm in FIGS. 1-27, and of the firearm in FIG. 28, form no part of the claimed design. The broken away symbols shown in the Figures indicate the appearance of any portion of the article between the break lines forms no part of the claimed design.
